UNITED STATES PATENT OFFICE.

WALTER GROVER VETTER, OF ALVA, OKLAHOMA.

AUXILIARY AIR-INTAKE FOR INTERNAL-COMBUSTION ENGINES.

1,206,625.

Specification of Letters Patent. Patented Nov. 28, 1916.

Application filed December 6, 1915. Serial No. 65,305.

To all whom it may concern:

Be it known that I, WALTER G. VETTER, a citizen of the United States, residing at Alva, in the county of Woods and State of Oklahoma, have invented certain new and useful Improvements in Auxiliary Air-Intakes for Internal-Combustion Engines; and I do declare the following to be a full, clear, and exact description of the invention, such as will enable others skilled in the art to which it appertains to make and use the same.

My invention which relates to improvements in auxiliary air intakes for internal combustion engines, has for its object to provide a simple and inexpensive device of this class which will be automatically controlled by the temperature of the engine.

With this general object in view, the invention resides in certain novel features of construction and in unique combinations of parts to be hereinafter fully described and claimed, the descriptive matter being supplemented by the accompanying drawing which constitutes a part of this specification and in which:

Figure 1 is a side elevation of the invention applied to the intake manifold of an engine; Fig. 2 is an enlarged vertical section; and Fig. 3 is a vertical transverse section as seen on the plane indicated by the line 3-3 of Fig. 1.

In specifically describing the invention shown in the drawings above briefly described, similar characters will be placed on corresponding parts throughout the several views and reference will be herein made to the numerous elements by their respective indices. To this end, the numeral 1 indicates a tubular attaching member having external screw threads on both of its end portions and provided at approximately its center with a polysided enlargement 2 between which and a nut 3 threaded on the member 1, one end 4 of a U-shaped thermostat 5 is clamped. The other end 6 of the thermostat 5 is provided with an opening aligned with the bore of the tubular attaching member 1, said opening receiving therein a needle valve in the form of a set screw 7. One end of the screw 7 is positioned in close proximity to one end of the attaching member 1, and is preferably pointed as shown at 8 for engagement with a suitable seat 9 formed within the aforesaid end of the attaching member. In order to hold the screw

7 normally against turning, lock nuts 10 are threaded thereon in contact with the opposite sides of the end 6 of the thermostat.

The thermostat 5 is constructed of two layers of metal designated in the drawing by the numerals 5^a and 5^b. The layer 5^a is preferably formed of copper, while 5^b is usually constructed of iron or the like. However, these materials are not absolutely essential, it being only necessary that the inner sheet 5^a possess a higher coefficient of expansion than the other sheet. Thus, when the thermostat is heated, it will be obvious that the free end 6 thereof will recede from the attaching member 1, moving the screw 7 away from said member. This manner of operation is very desirable for reasons to be hereinafter fully explained.

In applying the invention to use, the end of the member 1 remote from the seat 9 is tapped into the intake manifold M of an internal combustion engine as shown clearly in Figs. 1 and 2. Normally, the pointed end 8 of the screw 7 will contact with the seat 9 and will thus prevent the entrance of fresh air into the manifold, but when the latter becomes heated as the engine runs under its own power, the temperature of the thermostat will rise, causing it to shift the screw 7 away from the aforesaid seat. Thus, fresh air is allowed to enter the manifold, and the amount of such air will be automatically regulated in strict proportion to the heat of said manifold.

By embodying the valve above mentioned in the form of the screw 7, and by providing the lock nuts 10 on such screw, it will be obvious that if desirable the valve may be so adjusted as to cause the thermostat to expand more than usual before the valve will be opened.

From the foregoing description, taken in connection with the accompanying illustration, it will be obvious that the object of the invention has been attained in an effective manner, and that the improved device will possess a number of advantageous characteristics regardless of its simplicity.

I claim:—

1. An auxiliary air intake valve for internal combustion engines comprising a combined attaching member and air passage in the form of a short tube having one end externally threaded to be tapped into an intake manifold, the other end of said tube being formed with a valve seat, a U-shaped

thermostat having aligned openings in its two ends, the opening in one end of said thermostat being spaced from and aligned with the valve seat, a needle valve disposed through this opening and coöperating with said valve seat, the opening in the other end of said thermostat receiving therein the aforesaid tube, an external enlargement on the intermediate portion of said tube bearing against one side of the last named end of the thermostat, and a nut threaded on said tube and bearing against the opposite side of said end, the thermostat being adapted to expand under an increase in temperature to open the valve, thus admitting fresh air into the manifold.

2. An auxiliary air intake valve for internal combustion engines comprising a combined attaching member and air passage in the form of a tube having its opposite ends externally threaded, one of said ends being adapted to be tapped into an intake manifold while the other end is internally chamfered to form a valve seat, an external enlargement formed integrally with the intermediate portion of the aforesaid tube, a U-

shaped thermostat having in one of its arms an opening receiving the last named end of said tube and bearing against said enlargement, a nut threaded on said end of the tube and contacting with said end of the thermostat to anchor the latter, the other end of said thermostat being formed with an opening aligned with the tube and disposed contiguous to the aforesaid seat, a screw passed through the last named opening and having a conical end coöperating with said seat, and a pair of lock nuts threaded on said screw and contacting with the opposite sides of the last named end of the thermostat, said thermostat being adapted to expand under an increase in temperature, thus causing the screw to recede from the seat to admit fresh air into the manifold.

In testimony whereof I have hereunto set my hand in presence of two subscribing witnesses.

WALTER GROVER VETTER.
